UNITED STATES PATENT OFFICE.

ROBERT HAMPE, OF HELMSTEDT, GERMANY.

FLIER SPINNING, TWISTING, AND SIMILAR MACHINE.

1,200,343.

Specification of Letters Patent.

Patented Oct. 3, 1916.

Application filed June 6, 1914. Serial No. 843,529.

To all whom it may concern:

Be it known that I, ROBERT HAMPE, manufacturer, citizen of the Duchy of Brunswick, residing at Helmstedt, Germany, have invented certain new and useful Improvements in Flier Spinning, Twisting, and Similar Machines, of which the following is a specification.

My invention relates to improvements in flier spinning, twisting and similar machines, and more particularly in machines in which the flier spindles are mounted in stationary bearings. In machines of this class the pegs, bells, or the like for the supply of empty bobbins and the pegs or bells for the reception of full bobbins from the flier spindles are disposed in two or more rows which are immovable relatively to each other and mounted on special supporting members, such for example as two parallel rails connecting the supporting members, and the said supports or rails have been so mounted as to be horizontally and vertically movable in such a way that the pegs or bells or the like of the bobbins can be positioned coaxially of the spindles of the fliers. In order to vertically move the supporting member, which is necessary in order to remove the rails carrying the bobbins and the foot step bearings, comparatively much power is necessary, because the supporting member and the pegs, bells, or the like which are mounted thereon are comparatively heavy. Thereby the operation of the apparatus for exchanging the bobbins is made inconvenient.

The object of the improvements is to provide a machine of this class in which it is not necessary to shift the supporting members and the bobbin pegs or the bells provided in lieu thereof in vertical direction, for which purpose the rail which imparts vertical reciprocating movement to the bobbins during the spinning operation and in some cases also the rail carrying the foot step bearings of the flier spindles is mounted for vertical shifting movement on the supporting members or the guides thereof, while the supporting members are so mounted as to be incapable of vertical shifting movement and located so low, that the members such as pegs or bells which carry the bobbins can be brought in alinement with flier spindles simply by the horizontal displacement of the said supporting members. Thereby the construction and the operation

of the mechanism for exchanging the bobbins are made more simple. Furthermore the improved mechanism is particularly suitable when reconstructing old spinning machines.

For the purpose of explaining the invention several examples embodying the same have been shown in the accompanying drawings, in which the same letters of reference have been used in all the views to indicate corresponding parts.

In said drawings—Figure 1, is a front view of the flier spinning machine provided with my improved apparatus for exchanging the bobbins, Fig. 2, is a partial plan view of the machine shown in Fig. 1, Figs. 3 and 4, are front views showing a modification of the machine with the parts in different positions, and Fig. 5, is a view similar to that shown in Fig. 1 with some parts removed and showing a further modification.

In the example shown in Figs. 1 and 2 the frame of the machine consists of a plurality of uprights 1 each carrying on a bracket 2 a horizontal guide rod 3 providing a support for a slide 4. The slides carry at their outer ends a rail or plate 7 to which two rows of bobbin pegs 8 and 9 are secured so as to be non-shiftable relatively to each other. By shifting the slides 4 on their rods 3 the pegs 8 and 9 can be set in alinement with the spindles of the fliers 18 for exchanging the bobbins. As shown in the drawings the slides 4 are shifted by means of a shaft 14 mounted on the machine frame 1, and provided with gear wheels 13 one for each of the slides 4. Each of the gear wheels is in mesh with rack teeth 4' provided on the operating slide. The shaft 14 is adapted to be rotated by suitable means such as a hand crank.

To the slides 4 vertical sleeves 5 are secured which provide guides for rack bars 6 formed with rack teeth. On the upper end of the said rack bars 6 a lifter rail 30 is mounted which is located above a spindle foot step rail 34, and which is adapted to be raised and lowered by shifting the rack bars 6 within their sleeves 5. For shifting the rack bars 6 suitable mechanism is provided. As shown a shaft 11 is mounted in the slides or bridges 4, which is adapted to be rotated from a cam disk 43 through the intermediary of a rocking lever 44, and a chain or belt gearing 45, 46. To the shaft 11 gear

wheels 12 are keyed with the rack bars 6. As is shown in Fig. 2 the foot step rail 34 is provided with open portions 34' which permit the passage of the pillars 1 there-
5 through when shifting the slides 4 to the right in Fig. 1. Similar open portions are provided in the lifter rail 30.

On the pillars 1 slides 25 are mounted which are adapted to be shifted in vertical
10 direction by means of gearings 16 and 28, the said slide carrying a shaft 27. To the said shaft arms 29 are secured which are provided for holding the full bobbins and lifting the empty ones. The slide 25 is
15 formed in such a way, that the arms 29 do not extend into the paths of the fliers 18. Therefore it is not necessary to readjust the fliers 18 prior to doffing the bobbins. By means of the vertically movable lifter rail
20 30 the full bobbins are smoothly lowered, so that the threads 55 can be wound only on the lowermost part of the flier spindles.

The lifter rail 30 which continuously lifts and lowers the bobbins while the machine
25 is in operation and which is located above the foot step rail 34, is provided with engaging devices 31 one for each of the spindles 18. When the rail 30 is moving downward and on to the foot step rail 34 the said
30 engaging devices move upward relatively to the rail 30 and thereby raise the bobbins 47 from the drag washers 32 of the rail 30 to such an extent, that the arms 29 can easily engage below the flanges 47' of the bobbins.
35 Therefore all that is necessary in my improved machine for doffing is to shift the foot step rail 34 together with the lifter rail 30 which has before been lowered on the same, and to horizontally shift the slides
40 4 with the said rails.

Where the spindles are freely suspended and are not provided with foot step bearings, the foot step rail 34 can be rigidly secured to the sleeves 5. In this case the
45 only object of the rail 34 is to lift the engaging devices 31 mounted on the lifter rail, so that the flanges of the bobbins are disengaged, the sockets 31 striking on the foot step rail 34 and moving upward beyond the
50 lifter rail 30 when the latter is moved downward. In this operation they lift the lower bobbin flanges 47' from the drag washers 32 of the rail 30, so that the arms 29 can easily engage below the flanges 47'.

55 In the example shown in Figs. 1 and 2 the bearings 48 of the fliers 18 are suspended from the overhead rail 50 of the machine by means of balls or rollers 49 which are located diametrically opposite each other at
60 opposite sides of the bearings 48, the latter being provided with two notches which are open downward and the overhead rail 50 being provided with corresponding notches which are open at their top sides. By reason
65 of this suspension of the fliers 18 the latter

can easily be mounted and dismounted, because the bearing bushing is always held in centered position. Besides it permits the lower ends of the spindles to yield slightly when the bobbins are being exchanged and when the pegs 8 or 9 are placed in alignment with the fliers 18. Finally when striking against an obstruction such for example as the rails 30 or 34 moving upward, the spindles can yield a little, so that injury
70 of the parts is avoided. As is shown in Fig. 1 the driving belts 51 for the fliers 18 pass through openings 50' of the overhead rail 50. Thereby the driving belts 51 are protected against the dust, hairs and the like
75 which fall from the feeding mechanism 52. Besides the construction of the spinning machine is thereby made more simple.

For severing the thread when doffing and after an empty bobbin 47 has been placed
80 on one of the fliers 18 and the latter has performed a few revolutions for the purpose of attaching the end of the thread to the empty bobbin, severing mechanism of known construction may be provided. In the example shown in the drawings the said severing mechanism consists of a pair of cutter blades 38 and 38^a adapted to be shifted toward and away from each other by the hand of the operator after the cutting
85 mechanism has been raised to such an extent, that the threads 55 which are passed from the empty bobbins placed on the fliers 18 to the full bobbins on the pegs 9 extend between the cutting edges of the cutter
90 blades 38 and 38^a.

In Figs. 3 and 4 I have shown mechanism for providing an accurate guide for the foot step rail 34 in Figs. 1 and 2. As shown the foot step rail 34 is normally held in operative position by means of springs 40 the power of which is such that they just overcome the weight of the rail 34 and yield when the lifter rail 30 is lowered on the rail 34, as is shown in Fig. 4. To the supporting members or bridges 4 or the rail 7 carried thereby brackets 35 are secured on which shafts 39 are mounted for vertical reciprocating movement. On the said shafts the springs 40 are coiled which engage below collars 41 and press the shafts 39 and the foot step rail upward to such an extent that the spindles 18 engage in the proper way in the foot step bearings 42.

For severing the threads when doffing a
120 severing mechanism 38^b, 38^c may be provided.

Instead of the bridges 4 shown in Figs. 1 and 2 which are movable in horizontal direction carrying members may be provided
125 which have rocking supports on a stationary horizontal shaft, and which provide supports for the foot step rail 34. This construction is shown in Fig. 5. Each of the carrying members is in the form of a hol-
130

low cylinder or ring 56 which is mounted on the frame 1' of the machine so as to be rotatable about its geometrical axis, and which carries two rows of bobbin pegs 8' and 9'. The hollow ring 56 is formed with an open portion 56' through which the rails 30' and 34' which are adapted to be raised and lowered by means of racks 6' can pass into the hollow of the ring. In 5 this position the part of the ring which carries the pegs 8' and 9' moves beyond the rails 30' and 34' when the ring 56 is being turned. In the example shown in the figure the ring is adapted to be turned by 10 means of a gear wheel 13' engaging in rack teeth 56" provided on the ring 56, the gear wheel 13' being adapted to be turned by means of a removable crank 57 or the like. Common driving means may be provided for all the rings 56, in which case all 15 the gear wheels 13' are secured to a common shaft 14'.

Any known or preferred means may be provided for supporting the ring 56. To 20 show what may be done the ring 56 is rotatably mounted on a core 58 which is rigidly secured to the frame 1' of the machine and is provided with an open portion 58' for the reception of the rails 30' and 34'. 25 The operation of the doffing mechanism is the same as in ordinary machines, so that a detailed description is not necessary. For removing the full bobbins 47 from the pegs 9' after severing the threads 55 a carriage 30 35 59 may be provided which is supported with its wheels 60 on longitudinal rails 61 provided alongside the machine. When the said carriage is moved by the operator along the machine the full bobbins are collected 40 from the pegs 9' by means of a stripping member 62 or the like.

The position which the parts assume during the spinning operation is represented in Fig. 3. During the spinning operation the 45 spool rail 30 rises and depresses alternately by means of the gear wheel 12 and rack 6 shown in Fig. 1, the wheel 12 being turned alternately by the weighted rope 45 engaging the pulley 10 mounted on the shaft 11 and by the cam 43 through the actuation of the lever 44 carrying a roller engaging said latter cam. If full spools are to be replaced by empty ones, the parts of the fliers 18 are first disposed in alinement, see Fig. 1. The 50 55 spool rail 30 is then lowered until it comes in contact with the bearing rail 34, this operation being effected by the lowering movement of the weighted rope 45 engaging the pulley 10. When the spool rail 30 descends it carries the foot bearing rail 34 downwardly therewith for a short distance against the tension of spring 40, as shown by Fig. 4, and thereupon the hook 29, Fig. 1, is moved by hand under the spool, said 60 65 hook being swung around the shaft 27, and

after this latter engagement of the hook with the spool has ensued the said hook and spool are slightly lifted by means of gear 28 and rack 16. The carriage 4 is now moved to the right by the operation of the pinion 70 14 and rack 4', the movement of the said carriage being to such an extent as to place the spool pin 9 under the spindle 18. The hook 29 is released from the spool and the latter falls and is caught on the pin 9. The 75 carriage 4 immediately following the latter operation is displaced slightly to the left or until the pin 8 carrying the empty spool is moved under the spindle 18. The hook 29 is then caused to engage under the upper 80 flange of the empty spool 47, as shown by Fig. 1, and the said empty spool is moved upwardly until it is pushed upon the spindle 18. The carriage 4 is next shifted to a greater distance to the left or into the position shown by Fig. 1 and the spool rail 30 is again raised whereby the foot bearing rail 34 is permitted to follow under the action of the spring 40, as shown by Fig. 3. The thread is first wound to some extent 85 upon the empty spool and is then cut off in a well known manner.

I claim herein as my invention:

1. In a doffing apparatus for flier spinning, twisting and similar machines, the 95 combination with the flier spindles mounted in fixed bearings, of a horizontally displaceable supporting member for full and empty bobbins, means to place said supporting member with the bobbins in alinement with the spindles, means for vertically moving the bobbins placed on the spindles, means located out of the paths of the fliers to hold the bobbins on the spindles independently of the said vertically moving means, and 100 means to move said vertically moving means relatively to the supporting member and away from the bobbins.

2. In a doffing apparatus for flier spinning, twisting, and similar machines, the 110 combination with the flier spindles mounted in fixed bearings, of a horizontally displaceable supporting member for full and empty bobbins, means to place said member with the bobbins in alinement with the spindles, a lifter rail mounted on said supporting member, means to hold the bobbins on the spindles independently of the lifter rail, and means to move said rail relatively to the supporting member and away from the 115 spindles.

3. In a doffing apparatus for flier spinning, twisting, and similar machines, the combination with uprights forming the machine frame, and the flier spindles mounted 125 in fixed bearings, of a horizontally displaceable supporting member for full and empty bobbins, means to shift said member toward and away from the uprights and with the bobbins in alinement with the spindles, a 130

lifter rail and a foot step rail mounted on said supporting member, means to hold the bobbins on the spindles independently of the lifter rail, and means to move said lifter rail relatively to the supporting member and away from the spindles.

4. In a doffing apparatus for flier spinning, twisting, and similar machines, the combination with uprights forming the machine frame, and the flier spindles mounted in fixed bearings, of a horizontally displaceable supporting member for full and empty bobbins, means to shift said member toward and away from the uprights and with the bobbins in alinement with the spindles, a lifter rail mounted on said supporting member, means to hold the bobbins on the spindles independently of the lifter rail, and means to move said rail relatively to the supporting member and away from the spindles.

5. In a doffing apparatus for flier spinning, twisting, and similar machines, the combination with the flier spindles mounted in fixed bearings, of a horizontally displaceable supporting member for full and empty bobbins, means to place said member with the bobbins in alinement with the spindles, a lifter rail mounted on said supporting member, a foot step rail yieldingly mounted on said member below the lifter rail and adapted to yield to the lifter rail placed thereon, means to hold the bobbins on the spindles independently of the lifter rail, and means to move the lifter rail on to the foot step rail and the lifter rail relatively to the supporting member and away from the spindles.

6. In a doffing apparatus for flier spinning, twisting, and similar machines, the

combination with the flier spindles mounted in fixed bearings, of a horizontally displaceable supporting member for full and empty bobbins, means to place said member with the bobbins in alinement with the spindles, a lifter rail and a foot step rail mounted on said supporting member, engaging devices for the spindles provided in bores of said lifter rail, shiftable relatively thereto, providing supports for the bobbins placed on the spindles, and adapted to be shifted relatively to the lifter rail by the foot step rail, means adapted to engage below the flanges of the bobbins and to hold the bobbins on the spindles independently of the lifter rail, and means to move said lifter rail relatively to the supporting member and away from the spindles.

7. In a doffing apparatus for flier spinning, twisting, and similar machines, the combination with the flier spindles mounted in fixed bearings, of a horizontally displaceable supporting member for full and empty bobbins, means to place said member with the bobbins in alinement with the spindles, a lifter rail mounted on said supporting member operating to downwardly move the full bobbins from the spindles, means located out of the paths of the fliers to hold the bobbins on the spindles independently of the lifter rail, and means to move said rail relatively to the supporting member and away from the spindles.

In testimony whereof I have hereunto set my hand in presence of two subscribing witnesses.

ROBERT HAMPE.
